UNITED STATES PATENT OFFICE.

OTTO A. HOKANSON, OF WOODSTOCK, ILLINOIS, ASSIGNOR TO WOODSTOCK TYPEWRITER COMPANY, OF WOODSTOCK, ILLINOIS, A CORPORATION OF ILLINOIS.

TYPEWRITER.

Application filed September 22, 1924. Serial No. 738,982.

This invention relates to typewriter mechanism in which the impression ribbon is moved to position over the printing point at each stroke of a type bar, and the invention has for 5 its object the provision of improved ribbon vibrator mechanism together with the connection between the ribbon vibrator mechanism and line finder to insure proper positioning of the impression ribbon.

10 Other objects of the invention will appear hereinafter.

The invention is exemplified in the combination and arrangement of parts shown in the accompanying drawings and described in 15 the following specification, and it is more particularly pointed out in the appended claims.

In the drawings—

Fig. 1 is a vertical sectional view, with parts 20 in elevation, showing a portion of a typewriter having one embodiment of the present invention applied thereto;

Fig. 2 is a horizontal section substantially on line 2—2 of Fig. 1;

25 Fig. 3 is a section similar to Fig. 1 but showing some of the parts on a larger scale;

Fig. 4 is a vertical section substantially on line 4—4 of Fig. 5;

30 Fig. 5 is a horizontal section substantially on line 5—5 of Fig. 3;

Fig. 6 is a vertical section substantially on line 6—6 of Fig. 5;

Fig. 7 is a vertical section substantially on line 7—7 of Fig. 5;

35 Fig. 8 is a rear elevation of the line finder and ribbon carrier, together with associated parts;

Fig. 9 is a horizontal section substantially on line 9—9 of Fig. 8;

40 Fig. 10 is a horizontal section substantially on line 10—10 of Fig. 8;

Fig. 11 is a front elevation of the parts shown in Fig. 8;

Fig. 12 is a vertical section on line 12—12 45 of Fig. 11, with parts in elevation;

Fig. 13 is a horizontal section substantially on line 13—13 of Fig. 11; and

Fig. 14 is a section on line 14—14 of Fig. 13.

In front strike typewriters it is customary 50 to provide ribbon vibrator mechanism actuated usually by the type bars for moving the ribbon over the printing point to receive the impression at the time that the type strikes the platen, the ribbon being withdrawn after

each impression to permit easy visibility. It 55 is common to employ a two-color ribbon and to provide means for shifting either zone of the ribbon over the printing point so that the writing may be in either one of the two colors, as desired. It is also desirable to permit operation of the type bars without moving the ribbon to the printing point for cutting stencils. The present invention provides means for accomplishing all of these results and in addition provides a positive stop for 60 the ribbon vibrator which is controlled by the line finder so that there is no danger of overthrow of the ribbon vibrator. This prevents any possibility of overlapping of the colors 65 in the ribbon whether the writing is in upper 70 or lower case.

Referring first to Fig. 1 of the drawings, the numeral 15 designates the top plate of a "Woodstock" typewriter, although it will be understood, of course, that the invention may 75 be applied to other makes. A type bar segment 16 having type bars 17 pivoted thereon is supported on the frame 15. An arcuate universal bar 18 lies in the path of the type bars 17 and is operated thereby in a manner 80 similar to that shown in Patent No. 1,276,118, dated August 20, 1918. The bar 18 is connected by rearwardly extending members 19 with a universal bar frame 20 which is pivotally supported at 21 by links 22, the links being 85 pivoted at 23 to the frame 15.

As shown best in Figs. 5, 6 and 7, the frame 20 is provided with an irregularly shaped plate 24 secured to its underface by rivets 25. A second plate 26 is adjustably secured to 90 the frame 20 by screw and slot connections 27. A forwardly extending arm 29 is pivoted at 30 to the lower face of the plate 26, the plate 26 being bowed upwardly at its center to admit the end of the arm 29 between the plate 26 and the frame 20. The plate 26 has an integral tongue 31 overlying the arm 29 and having a head 32 which bears upon a pivot screw 41 carried by the arm 29, as will be described later. The tongue 31 is for the purpose of preventing any upward yielding of the arm 29 under the force applied thereto through the attached parts to be described. The arm 29 at its forward end is provided with a pair of spaced ears 36 and 37 having 105 slots 38 and 39, respectively, therein, as shown best in Fig. 6. An arm 40 is pivoted at 41 to the arm 29 and has its opposite end pivotally con-

nected at 42 to a bell crank lever 43, as shown in Fig. 5. The plate 24 is provided with a laterally extending arm 44 which carries a loop 45 disposed beneath the arm 29. A lug 46 is bent downwardly from the arm 29 and extends into the loop 45 to limit the lateral movement of the arm 29 when the bell crank 43 is oscillated, as will be hereinafter explained.

- 10 A rock shaft 47 is journaled in the side plates of the frame 15 and extends transversely of the frame near the rear thereof. The shaft 47 carries forwardly extending arms 48, Fig. 1, which support a platen carriage rail 49 extending across the machine frame. A platen carriage 50 is mounted on links 51 which permit vertical movement of the platen for case shift. A roller 52 runs on the rail 49 by means of which the platen is lifted when the shaft 47 is oscillated by the shift key. The shift key, not shown, has connection with an arm 53 secured to the arm 48. A spring 54 is provided for partially counter-balancing the weight of the platen.
- 15 25 As shown in Fig. 5, the rock shaft 47 carries a forwardly extending bracket 55. The bracket 55 has a rearwardly extending lug 56 formed thereon upon which the ribbon vibrator lever 57 is pivotally mounted at 58. The lever 57 has an upwardly extending arm 59 which is provided with laterally extending pins 60 and 61 on opposite sides thereof. The pin 60 is located closer to the pivotal point 58 than is the pin 61, the pin 60 being in position 30 to register with the slot 38 while the pin 61 is in position to register with the slot 39. The slots are selectively brought into engagement with their respective pins by movement of the bell crank lever 43 and link 40. The bell 35 crank lever 43, as shown in Fig. 5, is pivoted at 62 on an arm 63 extending forwardly from a plate 64 secured to the typewriter frame by screws 65, as shown in Fig. 3. The plate 64 has a downwardly and rearwardly bent portion 66 having ears 67 at its lower edge in which a rock shaft 68 is journaled. An arm 69 is secured to one end of the rock shaft 68 and extends upwardly therefrom. As shown best in Fig. 1, a link 70 is pivotally connected 40 at 71 to the arm 69 and has its forward end pivoted at 72 to one arm of a bell crank 73. The bell crank 73 is mounted on a stud 74 carried on an ear 75 projecting downwardly from a bracket plate 76 secured to the under 45 side of the frame plate 15. A finger lever 77 is provided with slots 78 and 79 which engage respectively with the stud 74 and with a pin 80 on the bell crank lever 73. The lever 77 is provided with a pin 81 to which a spring 82 is fastened for drawing the lever rearwardly. The forward end of the lever 77 extends through a slot 83 in a curved plate 84 extending downwardly from the bracket plate 76. The lever 77 is provided with an offset portion 85 having a fingerpiece 86 and pin 87

carried thereby. The plate 84 is provided with a plurality of openings 88 for receiving the pin 87. It will be apparent that when the finger piece 86 is grasped by the operator and the lever 77 is drawn forwardly to disengage the pin 87 from the openings 88 the lever 77 may be swung upwardly or downwardly to bring the pin 87 into registration with different openings 88. This movement will rock the shaft 68 to any one of a plurality of different positions determined by the openings 88.

20 The end of the shaft 68 opposite the arm 69 is provided with another upstanding arm 89 to the upper end of which a link 90 is pivotally connected at 91. The forward end of the link 90 is pivotally supported at 92 on a bell crank lever 93. A laterally extending lug 94 on the link 90 is pivotally connected at 95 to one arm of the bell crank lever 43. In 25 this way movement of the finger piece 86 shifts the bell crank lever 43 and thus moves the arm 29 and ears 36 and 37 laterally so as to bring the slots 38 and 39 selectively into engagement with the pins 60 and 61. When 30 the slot 38 is in engagement with the pin 60 movement of the universal bar frame 20 under impact of a type bar will swing the ribbon vibrator lever 57 upwardly a maximum amount since the pin 60 is close to the pivot 58 of the vibrator lever. When the finger piece 86 is moved to its lowermost position, marked "Black" in Fig. 1, the slot 39 will engage pin 61 and movement of the universal bar will impart a less throw to the ribbon vibrator lever 57. This will bring the upper zone of the ribbon into printing position so that the impression will be made in black, the upper zone of the ribbon usually being colored black or a dark color, while the lower zone is usually colored red. If the finger piece 86 is set in the intermediate position marked "Stencil" in Fig. 1, the ears 36 and 37 will occupy the position shown in Fig. 5 so that neither of the slots 38 and 39 will engage their respective pins 60 and 61. In this position the ribbon vibrator lever 57 will remain stationary during operation of the typewriter and the ribbon will not be moved over the printing line.

35 As previously pointed out, the lever 57 is pivoted on the bracket 55 which is secured to the shaft 47. Since the platen is shifted by oscillation of the shaft 47 for printing in different case colors, it will be understood that the vibrator lever 57 will be carried upwardly in unison with the upward movement of the platen so that the ribbon vibrator lever will always occupy the same position relative to the platen. This up and down movement of the vibrator lever will not interfere with the operation of the slots 38 and 39 and pins 60 and 61 since the slots are made of sufficient length to engage the pins irrespective of the vertical position of the vibra- 40

tor lever. The slots are also given the proper angular position to properly position the ribbon vibrator relative to the platen and to impart the same amount of movement thereto 5 irrespective of the vertical position of the platen.

The lever 57 is provided with a slot 96 at its forward end to which a ribbon carrier 97 is secured by means of a pin 98. The type 10 bar segment 16 is recessed on its rear face, as shown at 99, to receive the carrier 97 and the segment also carries a plate 100 at its top portion provided with type bar guides 101. The carrier 97, as shown in Fig. 8, is 15 provided at its upper end with spaced bifurcations 102 which are guided by flanged lugs 103 carried by the plate 100 and overlapping the outer edges of the bifurcations 102. The bifurcations 102 are provided with loops 104 20 at their upper ends for receiving the ribbon. A slot 105 in the carrier 97 receives a pin 106 for assisting in guiding the carrier in its up and down movement. The upward movement of the carrier is limited by a pin 25 107 secured to the rear face thereof near its lower end in position to engage a stop plate 108. In order that the upper movement of the ribbon may always be arrested in the same definite position relative to the printing line the stop plate 108 is mounted on the 30 support for the line finder 109. This support comprises a plate 110 having arms 111 extending upwardly therefrom. The line finder 109 has an upper horizontal edge 112 for indicating the line position and is provided with an opening 113 for receiving the type bars, there being an inverted V-shaped 35 portion 114 bridging the upper part of the opening 113 to assist in holding the paper in position at the printing point. The stop plate 108 is slidably mounted on the supporting plate 110 by slots 115 and headed rivets 116. The plate 108 is provided with two stop edges 117 and 118 which are offset 40 relative to one another for arresting the ribbon either for black or red. The same movement of the finger piece 86 which shifts the slotted loops 36 and 37 also shifts the stop plate 108 to bring the proper stop shoulder 45 into operative relation to the pin 107 corresponding to the amplitude of vibration imparted by the slots 38 and 39. The movement of the plate 108 is effected by the bell crank lever 93 which, as previously explained, 50 has one arm connected with the forwardly extending link 90 which operates the bell crank lever 43.

As shown best in Fig. 9, the bell crank lever 93 has its forwardly extending arm pivotally connected at 119 to an arm 120. The arm 120, as shown in Fig. 8, is secured to the plate 108 by rivets 121. The pivot pin 119 on the bell crank 93 is elongated, as shown in Fig. 8, so that the arm 120 may move upwardly thereon without being disengaged 55

therefrom when the stop plate 108 is moved upwardly during case shift. It is necessary, of course, that the line finder be moved upwardly during case shift movement in order to maintain its proper relation with the platen 70 and since the stop plate 108 is mounted on the line finder support, the stop plate also moves in unison with the line finder and platen.

The upward movement of the line finder is produced by means of a bell crank lever 75 122 secured to a shaft 123 pivotally supported on bracket arms 124 extending downwardly and rearwardly from the bracket plate 125 secured to the frame member 126 by screws 127. One of the bracket arms 124 is provided 80 with an extension 128 having a lug 129 on which the bell crank lever 93 is pivoted at 130, as shown best in Fig. 9. The lower arm of the bell crank lever 122 is pivotally connected to a link 131 which is formed in sections held in adjustable relation to one another by screws 132. The rear end of the link 131 is pivotally connected to a downwardly extending arm 133 carried at one side of the bracket 55. It will be understood 90 from Figs. 3 and 12 that oscillation of the shaft 47 to shift the platen will at the same time move the arm 133 to impart oscillation to the bell crank lever 122 and thus raise the line finder support to maintain the line finder 95 in fixed relation with the platen. The position of the line finder relative to the platen may be adjusted by adjusting the length of the link 131 by means of the screws 132, there being proper slots arranged in the link 131 100 to permit of such adjustment. The line finder support 110 is provided with rearwardly projecting ears 134 which are pivoted at 135 to the bell crank lever 122 and to an arm 122' secured to the shaft 123 at the end 105 thereof opposite the lever 122. The plate 110 also carries a rearwardly projecting lug 136 below the pivotal points 135 and this lug is engaged by a compression spring 137 110 which has its opposite end supported on an arm 138 extending downwardly from the bracket plate 125. The spring 137 tends to rotate the line finder support about the pivots 135 so as to resiliently press the upper edge of the line finder 109 against the platen. 115

Supplemental means for exerting additional force upon the line finder support is shown in Figs. 11, 12 and 13. This supplemental means comprises a pair of spring arms 139 having rollers 140 journaled thereon in position to engage the upwardly extending arms 111 of the line finder support. The spring arms 139 normally hold the rollers away from the supporting arms 111 but the arms 139 are provided with downwardly 120 extending contact members 141 which are arranged in the path of cam faces 142 on slides 143. These slides are provided with a screw and slot connection 144 with the top surface of the type bar segment 16. When 125 130

the slides 143 are moved inwardly the rollers 140 will be pressed against the uprights 111 thus forcing the line finder 109 firmly against the front of the platen. Spring plates 145 are disposed beneath the slides 143 and are adjustably held in position by the screws 144. The springs 145 have stop lugs 146 struck up therefrom to limit the movement of the slides 143 and also have their ends 147 bent upwardly to provide spring friction contact with the slides to retain them in any position to which they may be moved to produce the required pressure on the line finder. The slides may, of course, be moved outwardly 15 by the operator when it is desired to release the extra pressure upon the line finder.

The downward movement of the vibrator is limited by a stop 148 pivoted at 149 to one arm of the bracket 55 and provided with a screw and slot connection 150 for adjusting its position. The stop 148 is provided with a shoulder 151, Figs. 5 and 6, which engages the front edge of the upwardly extending arm 59. The position of the stop shoulder 151 may be adjusted by swinging the stop about its pivotal support 149, the shoulder being held in its adjusted position by the screw 150. The stop shoulder 151 is adjusted so that it holds the vibrator 57 in proper position to bring the pins 60 and 61 in registration with their slots 38 and 39 when the platen is in its upper position. This will hold the pins in place to re-enter their slots when the member 29 is shifted while the platen is in upper position. When the platen is lowered the change in the relation of the parts would permit the vibrator 57 to drop slightly below the position in which the slots and pins register and to prevent this an additional stop 152 is adjustably supported from the frame of the machine by a bracket arm 153 in position to engage the lower edge of the lever 57 when the platen is lowered.

The line finder 109 is preferably made of thin spring steel, but since it is made separately from its support 110 and 111, the parts may be made of different material thus making it possible to temper the part 109 much more readily than if the parts were all integral. The use of the spring 137 makes it unnecessary to form the parts 110 and 111 of spring material and the slotted connection between the finder and its support permits adjustment of the edge 112 independently of the support.

An eccentric screw 154 forms the pivotal connection between the arms 131 and 133 to permit adjustment of the position of the axis of this pivot. By rotating this screw the pivotal axis may be shifted to accurately locate it in the proper position to cause the line finder to travel upwardly in exact unison with the platen. Moving the pivotal center at this point adjusts the relative speed of the line finder and platen during case shift so

that the adjustment may be used to correct any slight difference in their rates of movement.

I claim:—

1. In a typewriter, a ribbon vibrator including a ribbon guide, a line finder, and a stop for said ribbon vibrator connected with said line finder, said ribbon vibrator having an abutment in fixed relation with said ribbon guide for contacting with said stop. 70

2. In a typewriter, a ribbon vibrator including a ribbon guide, a line finder, and means connected with said line finder for limiting the movement of said vibrator at a definite position in its movement relative to said line finder, said ribbon vibrator having an abutment in fixed relation with said ribbon guide for contacting with said stop. 80

3. In a typewriter, a ribbon vibrator, means for imparting different amplitudes of movement to said vibrator, a shiftable platen carrier, a line finder, means for shifting said line finder when said platen carrier is shifted, and stop mechanism connected with said line finder to shift therewith for arresting the movement of said vibrator in different definite positions relative to said line finder corresponding to the different amplitudes of movement imparted to said vibrator. 90

4. In a typewriter, a ribbon vibrator, a universal member for actuating said vibrator, a connection between said universal member and vibrator, said connection being variable at the will of the operator for imparting different amplitudes of movement to said vibrator, a line finder, means for imparting case shift movement to said line finder, and stop mechanism connected with said line finder to shift in unison therewith, said stop mechanism being adjustable relative to said line finder for arresting said vibrator at different positions corresponding to the different amplitudes of movement imparted to said vibrator. 100

5. In a typewriter, a shiftable platen, a ribbon vibrator, means for imparting different amplitudes of movement to said vibrator, a line finder, means for shifting said line finder in unison with said platen, and adjustable stop mechanism connected to shift with said line finder for arresting said vibrator in different positions relative to said line finder, the positions being the same relative to said line finder irrespective of the position of said line finder. 115

6. In a typewriter, a shiftable platen, a ribbon vibrator, a line finder, means for shifting said vibrator and line finder in unison with said platen, means for imparting different amplitudes of movement to said vibrator irrespective of the position of said platen, and adjustable stop mechanism connected to shift with said line finder for positively arresting the movement of said vibrator in definite positions relative to said line 130

- finder irrespective of the position of said platen and line finder.
7. In a typewriter, a platen, means for shifting said platen, a ribbon vibrator pivotally mounted on said shifting means, a universal member, means for connecting said universal member with said vibrator at different distances from the pivotal support therefor, and an adjustable stop mounted on said platen shifting means for limiting the return movement of said vibrator.
8. In a typewriter, a line finder, a support for said line finder formed separately therefrom and secured thereto, and a spring for exerting pressure on said support to resiliently hold said line finder in position.
9. In a typewriter, a platen, a line finder comprising a spring plate arranged to engage said platen, a support for said line finder formed separately therefrom and secured thereto, and a spring for exerting pressure on said support to hold said line finder against said platen.
10. In a typewriter, a shiftable platen, a frame for shifting said platen, a line finder, a lever having one arm thereof pivotally connected with said line finder, a connection between said frame and the other arm of said lever to cause said line finder to move in unison with said platen, said connection being pivoted to said other arm at a point spaced from the pivot of said lever, and a spring for resiliently pressing said line finder about its pivotal connection with said lever to hold said line finder against said platen.
11. In a typewriter, a shiftable platen, a line finder for engaging said platen, a frame for shifting said platen, a lever having a fixed fulcrum and having one end thereof pivotally connected with said line finder, a link connecting the other end of said lever with said platen shifting frame, a spring for moving said line finder about its pivotal connection with said lever to hold said line finder against said platen, a fixed abutment for said spring, a ribbon vibrator, and a limit stop for said vibrator connected with said line finder support.
12. In a typewriter, a platen, a frame for shifting said platen to change from one case writing to another, a line finder, a bell crank lever having one end thereof pivotally connected with said line finder, a link connecting the other arm of said bell crank lever and said shiftable frame, said link being adjustable to regulate the position of said line finder relative to said platen, a spring for forcing said line finder against said platen and a fixed abutment for said spring.
13. In a typewriter, a line finder support, a ribbon vibrator, a limit stop slidably mounted on said line finder support, means for shifting said line finder support in unison with said platen, and means for moving said limit stop to different position on said line finder support irrespective of the position of said line finder support.
14. In a typewriter, a shiftable platen, a ribbon vibrator, means for actuating said vibrator to impart different amplitudes of movement thereto, a line finder support, and a limit stop slidably mounted on said line finder support and having means thereon for positively arresting said vibrator at different positions relative to said line finder support.
15. In a typewriter, a shiftable platen, a ribbon vibrator mounted to shift with said platen, means operable irrespective of the position of said platen for imparting different throws to said vibrator, a line finder, means for shifting said line finder in unison with said platen, a limit stop connected to shift with said line finder and having means thereon for arresting said vibrator at different positions, and means for shifting said limit stop, said shifting means having sliding connection with said limit stop to permit operation thereof for different positions of said line finder.
16. In a typewriter, a platen, a line finder, resilient means for pressing said line finder against said platen, a supplemental pressure device for engaging said line finder, and a member having a cam face for pressing said supplemental device against said line finder.
17. In a typewriter, a platen, a line finder, a spring arm having a roller thereon positioned adjacent said line finder but held by said arm out of contact therewith, and means for forcing said device against said line finder to exert supplemental pressure on said line finder.
18. In a typewriter, a platen, a line finder, means for holding said line finder against said platen, a supplemental device for exerting pressure against said line finder, and a slide having a cam face for actuating said supplemental device.
19. In a typewriter, a line finder, a supplemental device for exerting pressure on said line finder, and a pair of contact members movable toward one another to actuate said supplemental device.
20. In a typewriter, a line finder, a pair of spring arms having rollers thereon for engaging said line finder, and a pair of slides movable toward one another for pressing said rollers against said line finder, said slides having shoulders thereon for retaining said rollers in engagement with said line finder.

In testimony whereof I have signed my name to this specification on this 18th day of September A. D. 1924.

OTTO A. HOKANSON.
